OR D 12,580

DESIGN FOR A STOVE-BRACKET.

Design No. 12,580, dated November 22, 1881.

UNITED STATES PATENT OFFICE.

WALTER SCOTT SHIPE, OF MINERVA, OHIO.

DESIGN FOR A STOVE-BRACKET.

SPECIFICATION forming part of Design No. 12,580, dated November 22, 1881.

Application filed September 5, 1881. Term of patent 7 years.

To all whom it may concern:

Be it known that I, WALTER SCOTT SHIPE, a citizen of the United States, residing at Minerva, in the county of Stark and State of Ohio, have invented and produced a new and original Design for Stove-Brackets, of which the following is a specification, reference being had to the accompanying photograph, forming part thereof.

10 Figure 1 is a top view of part of my newly-designed stove-bracket. Fig. 2 is an elevation of the same. Fig. 3 is an elevation of the rod and base upon which the shelves are supported, these views being deemed necessary to fully 15 illustrate my design.

Heretofore stove-brackets have been made which presented, when viewed in elevation, as in Fig. 1, very indefinite designs, being a combination of scrolls and vines simply to fill the 20 space. In this the design is neat and symmetrical.

The leading feature of my design is a circular metal casting or shelf, as shown in Fig. 1, with circular rim and star-shaped center, connected with the rim by complete circles and 25 arcs.

A is the star-shaped center. B are the small circles which connect the star-shaped center figure with the arcs; and C the arcs, which connect the whole with the rim E.

30 I claim—

The design for a stove bracket herein shown and described, the same consisting of the shelf with center A, circles B, and arcs C within a circular rim, E.

WALTER SCOTT SHIPE.
